UNITED STATES PATENT OFFICE.

JOHN D. PEDERSEN, OF JACKSON, WYOMING.

CARTRIDGE.

1,066,525.

Specification of Letters Patent.

Patented July 8, 1913.

Application filed October 21, 1912. Serial No. 726,926.

To all whom it may concern:

Be it known that I, JOHN D. PEDERSEN, a citizen of the United States, residing in Jackson, in the county of Uinta and State 5 of Wyoming, have invented certain new and useful Improvements in Cartridges, of which the following is a specification.

My present improvements relate to ammunition for small-arms, and more particularly to shot-cartridges for use in such firearms having straight-bore barrels.

One object of this invention is to secure a better "pattern", or shot distribution, at the target and within a given or required 15 area at a suitable range or distance, without having the usual "choke-bore" at the muzzle of the barrel.

A further object is to reduce the tendency of the shot to scatter, and to do this by 20 avoiding the flattening or other deformation of the peripherally-disposed shot in the shot-pack by friction and pressure against the gun-barrel; also, by avoiding those results, to prevent the leading of the surface 25 of the bore by the sliding action of shot while in contact therewith.

It will be remembered that in shotguns using shot-cartridges, it has been the practice to drive the shot out of the cartridge case 30 directly into the bore of the gun-barrel. For the purpose of preventing or reducing the spreading or scattering of the shot charge to a certain extent, and thus keep down the area and diameter of the "pattern", the practice has been to reduce the 35 diameter of the bore near or at the muzzle of the barrel, this construction or reduced portion of the bore being known as the choke. The use of the choke bore has appeared to 40 have the effect of making the shot strike closer together on the target than would be the case if a straight or cylindrical bore were used. This action, however, as I have found by extended investigation and experiment, is not uniform in practice, but gives 45 an uneven shot distribution which is usually designated as "patchy". The choke bore also tends to increase the distortion or flattening out of those pellets of shot which 50 come in actual contact with the surface of the bore and choke, and thus form, by the action of friction and pressure, a number of small "flats" on the surface of each of 55 those shot pellets. As a result of these causes, I have found that at the usual target-

ing distances, (at the range of 40 yards for instance) the shot-charge scatters or "strings" out to an undue extent, so that in a shot charge fired through a choke bored barrel, the leading shot in the charge are 60 frequently as much as forty or fifty feet in advance of the rear pellets in the same charge, while many of the shot fall prematurely,—as may readily be observed by firing horizontally at suitable elevations over 65 the surface of still water, in a well known manner. Furthermore, the choke-bore will evidently be variable in its action on shot-charges of different quantities, and also on charges of the same quantity or weight but 70 made up of shot of different sizes.

In the accompanying drawing forming a part of this specification, Figure 1 is a side view of a complete shot-cartridge made in accordance with my present invention; this 75 view shows the main shell, or powder-shell, S, having the usual extraction-rim, 2, and combined with a shot-case, C, detachably secured in or to the forward end of the main shell. Fig. 2 is a similar side view, drawn 80 in alinement with Fig. 1, for showing the complete shot-packet ready for insertion into a powder-shell. Fig. 3 is a view on an enlarged scale, showing a longitudinal section through the shot-cartridge illustrated 85 in Fig. 1; this view shows the several component members in position ready for firing the cartridge, the slideable powder-wad, E, being located with an annular space, B, forward thereof. Fig. 4 is a sectional view corresponding to Fig. 3, but showing the powder-wad, E, operating as a piston-member and advanced a short distance from its initial position shown in Fig. 3; and showing 90 the deformable head, H, of the shot-case, C, as having had its central zone, n^1 , driven forward (toward the right-hand,) by the initial action of the powder gases acting through the member E; this member is here shown as an ordinary three-part wad, comprising the disks or layers 3, 4, and 5, but this composite form is not material. Fig. 5 is a face or plan view; and Fig. 6 an edge view of one preferred form of a sealing-in 95 wad, or shot-wad, for holding the shot-charge or pack in the shot-case C, and thereby completing the shot-packet ready for use. Fig. 7 is a diagrammatic view illustrative of certain features hereinafter more fully explained.

Similar characters designate like parts in all the views.

If a cylindrical shot-case, such, for instance, as C, were made with its rearward end, or head H, fully conforming to the powder-wad F, and so not be re-formable by that member on its initial forward movement; and if, at the same time, the shot-wad D were secured into the front end of the shot-case, thus making a closed shot-packet, then on firing the gun, the powder gases pushing forward on the wad E as upon a piston, would push the shot-case and the shot contained therein through the bore of the gun and out into the open air, and thereupon the shot-case while sealed at its front end, would travel through the air substantially as a solid projectile and, of course, would not constitute nor be effective as proper ammunition for a shot gun.

It is, therefore, one of the objects of my invention to provide means for breaking such seal or shot wad, and thus release the shot-charge before the shot-packet leaves the bore of the gun. For effecting this object, I have illustrated in the drawing a preferred form of an organization of cartridge components or members, wherein the initial force of the powder gases operates through certain of those component members to transmit force through the central portion or zone, as Z^1 , (see Fig. 7) of the shot-charge to the shot-wad D, for displacing this wad or shot sealing-in member during the acceleration of the shot-packet and while this packet is still within the bore of the gun barrel. The effect of these operations is, of course, to substantially eliminate or close up the annular space at B, Fig. 3, which is provided in the completed cartridge for the purpose of permitting the forward movement of the member E relatively to the shot-case C.

The position of the parts before firing the cartridge, is shown in Fig. 3; and Fig. 4 shows their position immediately after the powder has been ignited. In this latter view, the powder-wad E has been driven forward a short distance in the powder-case or shell S, and by driving forward the central zone n^1 of the head H, has re-formed this shot-case head and has thereby also driven forwardly the mid-zone portion of the shot-pack, designated in a general way by P, in Figs. 3 and 4. The body portion of the shot-case, however, is yet held in the same relation to the main cartridge case or shell S, by the combined action of the front end, b, of the shell S crimped into the annular groove 8 of the shot-case, acting in conjunction with the inertia of that portion of the shot charge situated adjacent to the outside of the shot-case, as in zone Z^3 , which portion of the shot charge is not directly nor very greatly affected by the reforming

as herein described of the said head of the shot-case.

In Fig. 4 the shot-wad D is shown to have been pushed forward just out of the front end of the shot-case, and to have bent out the slight crimp at the front end of the shot-case during its forward movement in this case. It is probable, I apprehend, that at this time the breaking up or destruction of the shot-wad D is substantially effected, and that this breaking up will be completed later on during the accelerating movement of the shot-charge within the bore of the gun. In the preferred arrangement here described, the main shell or powder-case S, it will be noted (see Fig. 3), has a length greater than required for containing the powder charge, as G, Fig. 3, and extends forwardly thereof for providing the wad-space for the wad E; and then extends still farther forward to provide the annular piston-space B, and to provide for receiving and locking with the rearward part of the case C of the shot-packet by means of the detentively-connecting and resistant but releasable engagement at 8, which should preferably be so adjusted by its construction as to delay the forward sliding movement of the shot-case within the main-shell S, until after the reforming of the head H is begun. The shot after being loaded into the case C, are readily held therein by some suitable shot-wad, as D, which I preferably make of thin cardboard,—preferably of a crisp or fragile, yet relatively rigid quality,—set into the open end of the case, and there held by slightly crimping the edge, as at 9, Figs. 2 and 3, or by other means, such, for instance, as suitable cementation. The shot-case is shown provided near its rear end with an annular groove, at 8, into which the front end, b, of the cartridge shell, S, is crimped, this being one preferred method for detachably securing the shot-case C, into the cartridge shell S. In practice the groove at 8 may usually be made relatively smaller than illustrated in the drawing.

This composite construction of the cartridge has the advantage of permitting the shell S to be very much shorter than could be used by following the present practice and loading the shot directly into the forward end of the main shell or case S and simplifies and very materially reduces the cost of manufacture, and also permits the use of two kinds of metal for the two cases S and C, respectively, or of two qualities of metal, so that one may be highly tensioned while the other is softer or otherwise differently formed. That portion of the shot-case forward of the annular groove or retention-facet S, will usually, or preferably, correspond in diameter to the outside of the main-shell S, while that portion d of the

shot-case to the rear of said face or groove 8, corresponds to the inside diameter of the forward end of the main-shell S, so that when the shot-case is assembled with the shell S, the general diameter of the cartridge may be maintained; by this means I provide for the proper fitting of the cartridges in a gun having a truly cylindrical bore.

10 By making the case C of metal of a readily expandible character, as compared with the gas-pressure to be used, the operation of the combination of elements may be so regulated that as the case C slides out of the shell S, the reduced cylindrical portion d thereof, will become enlarged and so bring the entire length of this case to a substantially cylindrical form and diameter; this is indicated by the line e in Fig. 7. The reduced portion d of the shot-packet being of a considerable length, as herein illustrated, provides for a sliding movement of the case C within the shell S during the later stages of the reformation of the head H, should this reforming operation not be completed until after the separation of the retainer-joint, or resistant lock-joint at 8; but this locking together of the shell S with the case C, should, in general, be relatively firm in order to provide the proper initial resistance, or such as may be required in addition to the inertia of the shot-packet.

For the purpose of illustrating approximately the operation of head H and of the shot-pack P, I have indicated in Fig. 7 this pack as being divided into concentric zones, comprising the central zone Z¹, the integrally-connected medial zone Z² and outer, or peripheral portion or zone Z³, as indicated by dotted lines. For comparison, the head H is here shown in its initial position by a solid line, and in its re-formed position by a dotted line. The concentric areas of the head H which correspond to the shot-pack zones Z¹, Z² and Z³, respectively, are designated by n¹, n² and n³. As the head H should be formed of strong yet mobile material, it will be evident that the forcible advance of the powder-wad E, (see Figs. 3 and 4) against the head zone n¹, will operate to drive the head inwardly, with resultant change of form about such as indicated in Figs. 4 and 7. The initial sliding movement of the powder-wad, begins the reforming of the head for reducing the space within the shot-case, and then the further sliding movement of said wad continues such reforming operation during the sliding forward of the shot-case in the main shell, provided, of course, such reformation shall not in any given case be completed before the forward movement of the shot-case shall have begun; and for this purpose, among others, I have shown the shot-case fitted within the main shell and slidab

le of this sliding movement preferably being as much, or greater, than the annular space B, which corresponds to the distance f, Fig. 7. When the pressure on the zone n¹ begins to advance this central zone, the shot in the medial zone Z² are thereupon slightly advanced relatively to those in the outer zone Z³. This operation is naturally favored by the inertia of the mass of shot in said peripheral portion or outer zone Z³, 75 since this inertia operates against the outer zone n³ of the head H, until the wad E has advanced to the position indicated in Fig. 4, in which the head H is shown reformed for bearing firmly on both its central and outer zone, n¹ and n³, against the said wad E. By comparison of Figs. 3 and 4 with the diagrammatic lines and positions indicated in Fig. 7, the mode of action and the results of those peculiar operations will be 80 evident. When the slidab

le wad E, acting as a powder-driven piston, has advanced against the shot-packet to the extent indicated in Fig. 4, the head H of such packet will become flattened or crushed to conform 90 with the shape of the forward surface of that piston member. Usually, however, owing to the custom of making powder wads of slightly mobile and compressible material, the said wad E is likely to be itself 95 somewhat modified in form by the pressure; and a small change of shape, such as might result from such causes, is indicated in Fig. 4 by the curvature of the forward layer 5, and of the forward surface of the layer 4 100 of the member E. On firing the gun, the shot-charge, while still wholly or partially contained in the shot-case, moves up the bore of the gun and out into the open air impelled by the expansion of the powder 105 gases, and during this time the shot-wad, D, has been displaced from the shot-case (Fig. 4) and should be so broken up or otherwise dislodged that it does not prevent the shot from moving forwardly out of 110 the shot-case C. When the driving action of the expanding powder gases ceases after the shot and shot-case have left the muzzle of the gun, the air resistance, filtering, as it were, backwardly through the spaces or interstices between the shot pellets, appears to 115 become compressed and to be directed against the bottom of the shot-case and so tends to retard this case in its flight through the air, this action being assisted by the friction of the air on the exterior surface of the shot-case, as well as by any suction in the rear of this now forwardly moving case.

As the resistance of the shot-case in its flight through the air is greater than the 120 air resistance effective against each individual shot pellet, it appears that each pellet of shot normally will move forward relatively to and out of the shot-case, which then will quickly be stopped by the air re- 125

sistance and fall to the ground not far from the muzzle of the gun, the shot continuing on their usual range.

During the passage of the shot-case with its contained charge through the gun-barrel, this case moves or slides forward in the bore substantially as if it were an elongated cylindrical bullet, and so leaves the muzzle of the barrel while moving in a true and accurate line, and free of any forces or resistances which would tend to impair the proper direction or path of movement of the shot. After leaving the barrel, the shot-case is not subjected to any breaking up or deformation, nor is it separated or dismembered in any way, but continues on without change of shape or structure, in its true line of movement until the shot-pack has gone forward out of the case. Thus I avoid any interference with the shot-pellets after these leave the barrel, by any kind of separation or breaking up destructive action upon a shot case.

As the shot-case C holds the shot charge together during its passage up the bore and for a short distance after they together have left the bore, the individual pellets of shot will have acquired a direction substantially parallel with the axis of the bore of the gun and not diverging to any great extent therefrom, as happened heretofore when using a cylinder-bore gun in which the shot came in direct contact with the barrel. This concentrating action which I now obtain, of the shot pellets, may be made to vary somewhat by suitably proportioning the shot-case and its re-formable head so as to include more or less of the shot charge after said head has been re-formed sufficiently to break the seal at the front end of the case C. Also the distribution or scattering of the shot may be modified or regulated to some extent by suitably shaping the head H of the shot-case and thereby determining the relative spaces within the case C before and after the reformation of the head. This reduction of interior space is indicated in Fig. 7, where the annular zone Z² is shown projected slightly outside, at the right hand, of the end of the case C, while the central zone Z¹ is projected farther outward, thus fully expelling the shot-wad D, as indicated by the dotted lines in this diagram.

In practice, not only the displacement of the shot-wad, as D, is desirable but also the destruction or breaking up thereof. This may be provided for in any one of several ways, but for ordinary practice, I prefer the form of shot-wad construction illustrated in Figs. 5 and 6. This construction should preferably be such that, while not materially impairing the rigidity of the wad while this is holding the shot in the case, the wad will, under the violent stress of the shot being pushed forward in the case, from

or by the initial forward movement of the powder-wad or member E, be broken up into such fragments as will not seriously interfere with the flight of the individual shot pellets after they have left the muzzle of the gun. If this shot-wad were to leave the muzzle of the gun while completely intact, the air resistance on the wad, this being of the usual disk-form, might tend to retard too greatly the progress of some portion of the shot-charge or pack immediately behind the wad.

The means which I have herein shown for effecting the destruction of the shot-wad is a sectional formation thereof, which is obtained by making therein one or more cuts or grooves (as 12, Figs. 5 and 6, and preferably three or more in number) extending partially through this wad, and preferably made in the inner surface thereof. These cuts or grooves should be such as will not seriously affect the ability of the wad to properly hold the shot in the shot-case while the cartridge is being transported or while carried in the magazine of a gun, but such as will aid and secure a sufficient breaking up or destruction of the wad on the violent thrust imparted to it by the shot moving forward in central zone of the shot-case.

The shot-wad being expellable from the cylindrical part of the shot-case by a comparatively small amount of forward movement in a portion only of the shot-pack, the expulsion of the shot-wad begins immediately when the advancing powder-wad drives forward the center zone, Z¹, of the reformable head H, and thereby so initially reduces the amount of space within the case C, as to begin or preliminarily inaugurate the advance movement of the shot-pack, and the expulsion of the shot-wad prior to the disengagement of the shot-case, which is thus effected by force transmitted through the shot-pack, this force beginning to be effective while the resistant lock-joint is still unreleased, so that the resistance afforded by this releasable lock-joint which engages the forward end of the main-shell with the shot-shell, operates as a means supplemental to the inertia of the shot-packet for increasing the intensity of the reformatory action exerted on the head H during the time the powder-wad is advancing forwardly through the distance of the annular space B, which I have indicated approximately at f, Fig. 7.

In my improved shot-cartridge, the displacement or detachment of the shot-wad is accomplished, as to the breaking or unsealing thereof, preliminarily to the ejection of the shot from the gun, and not subsequently thereto; and by this means the breaking or detaching of the shot-wad is accomplished by the initial force of the powder acting instantly on the inauguration

of the forward movement of the powder-wad, and thus I accomplish in a peculiarly direct, simple, and practical manner a result which hitherto, as far as I am aware, has not been known in this art.

Shotguns being usually patterned for a range of forty yards and with a target circle thirty inches in diameter, the best or ideal pattern will of course, be one in which all the shot will be contained within that circle and be evenly distributed there-over. With the choke bored guns, however, the majority of the shot are frequently concentrated near the center and only a few near the outside, and frequently large spaces within the target circle are not covered at all; the latter is termed a "patchy" pattern. The beneficial control afforded by my improved shot-case over the distribution of the shot will be evident, since the shot will all leave the muzzle of the barrel in a bunch or relatively close and cylindrically-shaped pack, and not be divided into successive groups as is commonly the result with the choke bored gun. The form and proportion of the rear end or head H, of the shot-case affords means to so proportion the total number of shot contained in each successive and concentric cylindrical zone of the pack, as Z^1 , Z^2 , Z^3 , Fig. 7, before the shot leave the shot-case, that a nearly ideal distribution of the shot charge on the target may be obtained.

In practice, the shot-case may be made of any length suitable for holding the quantity of shot to be used in one charge; and may also be made of such thickness, character of material, and degree of resistance to the deformation and re-formation of the head thereof, as may be required for any particular range and kind of service. Thus shot-charges of different weights, and charges of the same weight, but having different sizes of shot, respectively, may be used equally well in the same gun. Also, in manufacturing the complete shot-cartridge, a shot-case of any suitable length or capacity may be combined with any given length of powder-shell, thus providing for the widest range of service conditions.

Having thus described my invention, I claim:—

1. In a shot-cartridge, the combination with a main shell having a powder-space and having a wad-space extension forward of the powder-space, a powder-wad slidable in the main-shell forward of the powder-space, a shot-shell containing the shot-pack and detachably seated in the forward end of the main-shell, and having at its rearward end a head having a reformable annular zone which is located with an annular space between this zone and the powder-wad, and also having a zone located in operative relation to the powder-wad; an expellable

shot-wad in the forward end of the shot-shell, and a resistant but releasable lock-joint engaging the forward end of the main-shell with the shot-shell, whereby on firing the cartridge, the initial movement of the shot-case is resisted by said resistant lock-joint for increasing the initial effect of the advancing powder-wad on the reformable head, and thereby prior to the disengagement of the shot-case, beginning the expulsion of the shot-wad by force transmitted through the shot-pack within said shot-case.

2. In a shot-cartridge, the combination with the cylindrical main-shell and with the powder-wad slidable therein, of a shot-case having a cylindrical forward portion externally coinciding in size with the main-shell and forming an extension thereof, and having a rearward portion fitting within the main-shell and slidable therein, and having a rearward head comprising a portion which is reformable for reducing the space within the shot-case, whereby the reforming of said head may be begun by the initial sliding movement of the said wad and then continued during the sliding forward of the shot-case in the main-shell.

3. In a shot-cartridge, the combination with the cylindrical main-shell and with the powder-wad slidable therein, of a shot-case having a cylindrical portion externally coinciding in size with the inside of the main-shell and slidable therein, and having a rearward head comprising a portion which is reformable for reducing the space within the shot-case, whereby the reforming of said head may be begun by the initial sliding movement of the said wad and then continued during the sliding forward of the shot-case in the main-shell.

4. In a metallic cartridge, the combination with the powder shell, of a shot-case engaging with and forming an extension of the powder-shell and having a reformable head in which the central zone thereof is located rearwardly of the outer zone of the head, and having said central zone adapted to be driven forwardly prior to the expulsion of the shot-case from the powder-shell, whereby to inaugurate the forward movement of the central part of a shot-pack within said shot-case in advance of such movement of the outer portion of the shot-pack.

5. In a shot-cartridge, the combination with the cylindrical main-shell and with the powder-wad slidable therein, of a shot-case having a cylindrical forward portion forming an extension of the main-shell, and having a rearward portion fitting within the main-shell and slidable therein, and having a rearward head comprising a portion which is reformable by the initial forward movement of the powder-wad, and a releasable resistant engagement detentively-connecting

- the main-shell and the shot-case and having its resistance adjusted by the construction for delaying the forward sliding movement of the shot-case in the main-shell until after 5 the reforming of the head is begun.
6. The herein-described improvement in shot-cases, which consists in a tubular shell for holding the shot-pack and adapted at its open forward end for receiving a sealing-in wad, and having at and closing its rearward end a reformable head in which the central portion thereof is forwardly-movable relatively to the rearward end of the tubular shell.
- 10 7. The herein-described improvement in shot-cases, which consists in a metallic tubular shell for holding the shot-pack and adapted at its open forward end for receiving a sealing-in wad, and having at and closing its rearward end a thin metallic, reformable head in which the central portion thereof is located rearwardly of the rearward end of the tubular shell.
- 15 8. The herein-described improvement, in shot-cases, which consists in a metallic tubular shell for holding the shot-pack and adapted at its open forward end for receiving a sealing-in wad, and having at and closing its rearward end, a reformable head 20 in which the central zone n^1 thereof is located rearwardly of the rearward end of the tubular shell, and having the medial annular reformable zone n^2 integrally connecting said zone n^1 with the peripheral portion 25 of said head, substantially as described.
9. A shot-case having at its forward end a shot-wad-engaging face and having at its rearward end a closed head comprising a reformable zone arranged for operating 0 through shot within the case and thereby expelling a case-closing shot-wad located in the forward end of the shot-case.
10. A shot-case comprising, in combination, a tubular shell and a rearward head 5 therefor which has a forwardly movable central zone surrounded by a reformable integrally-connected zone, whereby to initially reduce the space within the shot-case and thereby preliminarily inaugurate the 0 advance movement of the central portion of a shot-pack within case.
11. A one-piece metallic shot-case, comprising, in combination, the cylindrical case having at its forward end a shot-wad-engaging face and having at its rearward end

a closed head comprising a central forwardly movable zone, the peripheral zone relatively non-reformable, and the medial and reformable zone integrally connecting the central and peripheral zones and arranged for operating with the central zone through shot within the case and thereby expel a case-closing shot-wad located in the forward end of the shot-case.

12. A one-piece metallic shot-case for use 65 in metallic cartridge shells, comprising, in combination, the cylindrical case having its rearward portion of a reduced size, and at the forward end of such reduced portion having a shell-engaging resistant face, as 70 8; and having at its rearward end a closed head comprising a central forwardly-movable zone, the peripheral zone relatively non-reformable, and the medial and reformable zone integrally-connecting the central 75 and peripheral zones and arranged for operating with the central zone through shot within the case and thereby expel a case-closing shot-wad located in the forward end of the shot-case, substantially as described. 80

13. The combination in a shot-packet, of the cylindrical shot-case for containing the shot-pack, a shot-wad closing the forward end of the cylindrical case and comprising adjoining relatively rigid areas connected 85 by relatively breakable portions, and a closed head for the rearward end of said case comprising a reformable zone adapted to be driven forward by a powder-wad, whereby to drive forwardly a portion of 90 the shot in the shot-packet and thereby break the shot-wad in said breakable-portions, substantially as described.

14. The combination in a shot-packet, of the cylindrical shot-case for containing the 95 shot-pack, a shot-wad closing the forward end of the cylindrical case and comprising adjoining relatively rigid portions separated by channels in the inner surface thereof, and a closed reformable head for 100 the rearward end of said case comprising a zone adapted to be driven forward by a powder-wad, whereby to displace and break the shot-wad by the initial movement of a powder-wad, substantially as described.
